UNITED STATES PATENT OFFICE.

GEORGE S. GRINER, OF CLEVELAND, OHIO.

BASKET.

1,420,542.

Specification of Letters Patent. Patented June 20, 1922.

Application filed April 29, 1921. Serial No. 465,466.

To all whom it may concern:

Be it known that I, GEORGE S. GRINER, a citizen of the United States, residing at Cleveland, in the county of Cuyahoga and 5 State of Ohio, have invented new and useful Improvements in Baskets, of which the following is a specification.

This invention relates to a foldable basket, the principal object of the invention being 10 to provide a basket, preferably formed of a wire framework and a canvas covering, so formed that it can be folded into compact form so that it will occupy but little space when not in use.

15 Another object of the invention is to provide spring means for normally holding the basket in unfolded position and for causing it to assume such position when the means for holding it in folded position are released.

20 This invention also consists in certain other features of construction and in the combination and arrangement of the several parts, to be hereinafter fully described, illustrated in the accompanying drawings 25 and specifically pointed out in the appended claims.

In describing my invention in detail, reference will be had to the accompanying drawings wherein like characters denote like 30 or corresponding parts throughout the several views, and in which:—

Figure 1 is a side view of the basket in unfolded position.

Figure 2 is a view of the basket in folded 35 position.

Figure 3 is a plan view of the framework of the basket.

As shown in these views the basket consists of a wire framework 1, the covering 40 2 of canvas or the like and the lining 3. The framework comprises a rectangular handle part 4, a pair of bottom frames 5 and a pair of end frames 6. A pair of eyes 7 are formed adjacent each end of the lower bar of the 45 handle part and these eyes are engaged by eyes 8 formed at the ends of the frames 5 so that said frames 5 are hingedly connected with the bottom bar of the handle part. These bottom frames are each formed of a 50 single strip of wire 9 bent into substantially U-shape and the cross strips 10 which are connected with the strip 9. A pair of eyes 11 is formed on the bight of each strip 9 for receiving the eyes 12 formed on the end 55 frame 6. Each end frame is also formed of a strip 13, bent into substantially U-

shape, and a pair of cross strips 14, extending at right angles to each other, are connected with each strip 14 to reinforce the same. The lower end of the vertical strip 60 14 engages an eye 12¹ formed at the center of the bight of each strip 9. Thus each end frame is hingedly connected with the outer end of each bottom frame. A spring 65 15 is located on the bight of each strip 9 of each bottom frame and has one end suitably secured to the bottom frame and its other end engages the vertical strip 14 of each end frame. These springs are arranged to hold the end frames in upright 70 position. The cover and lining are suitably secured to the frame by rivets or the like and eyes 16 are formed midway the side pieces of the handle part 4 and also at the outer corners of the bottom frames 5 to receive 75 the ends of the chains 17 which are located outside the cover and tend to prevent the end frames from swinging downwardly beyond a horizontal plane. I also prefer to so form the eyes that they will 80 act as stops for limiting the outward movements of the parts of the frame before the covering is put in place. The handle part 4 may have its upper cross piece formed of several strips to widen it and thus make 85 it more comfortable to the hand.

It will thus be seen that the ends of the basket may be folded over upon the bottom frames, the sides of the covering being pressed in between the end and bottom 90 frames. Then the bottom frames are swung upwardly so that both the end frames will lie within the handle part. The parts are held in this position by means of the fastening means 18 which may be of any desired 95 type. When the basket is to be used it is simply necessary to release the fastening means when the springs will cause the parts to unfold and thus form a complete basket.

It is thought from the foregoing description that the advantages and novel features of my invention will be readily apparent.

I desire it to be understood that I may make changes in the construction and in the combination and arrangement of the several 105 parts, provided that such changes fall within the scope of the appended claims.

What I claim is:—

1. A basket of the class described comprising a handle part of rectangular shape having eyes on its lower bar, a pair of end frames having eyes thereon engaging the

eyes of the handle part, a pair of end frames hingedly connected with the outer ends of the bottom frames, a flexible covering connected with the frames and chains extending from the outer corners of the bottom frames to the side bars of the handle part.

5 2. A basket of the class described comprising a rectangular shaped handle part, a pair of bottom frames hingedly connected with the lower part of the handle part, a 10 pair of end frames hingedly connected with the outer ends of the bottom frames and a flexible covering connected with the frames and having side portions connected with 15 the side bars of the handle part.

3. A basket consisting of a wire framework having a canvas covering and lining therefor, said framework comprising a rectangular handle portion, a pair of bottom frames and a pair of end frames, said handle portion having eyes formed adjacent each 20 end of the lower bar engaging eyes formed at the ends of said bottom frames, said bottom frames being formed of a single

strip of wire bent into U-shape form and 25 cross strips connected with said strip of wire, each strip having a pair of eyes formed on the bight for receiving the eyes formed on the end frame, each end frame formed of a strip bent into U-shape and a pair of 30 cross strips extending at right angles to each other, the lower end of the strip forming the end frame engaging an eye formed at the center of the bight of each of the bottom frames, a spring located on the bight of the 35 strip forming the bottom frame and having one end secured to the bottom frame and its other end engaging the last mentioned cross piece of each end frame, said springs being arranged to hold the end frames in 40 upright position, chains located outside said cover to prevent the end frames from swinging downwardly beyond the horizontal plane.

45 In testimony whereof I affix my signature.

GEORGE S. GRINER.
